STERN FITTING FOR MOTOR BOAT

Frederick S. Brennan, Evanston, Ill.

Application November 3, 1958, Serial No. 53,246

Term of patent 7 years

(Cl. D71—1)

Fig. 1 is a perspective view of a stern fitting for motor boat showing my new design therefor, the fragmentary stern portion shown in broken lines being for illustrative purposes only.

Fig. 2 is a front elevational view thereof.

Fig. 3 is a plan view thereof.

Fig. 4 is a side elevational view thereof.

Fig. 5 is an elevational view of the side opposite that shown in Fig. 4.

I claim:

The ornamental design for a stern fitting for motor boat, as shown and described.
